DESIGN FOR A WATER COOLER

Christopher M. Cordley, New York, N. Y., assignor
to Cordley & Hayes, New York, N. Y., a corpora-
tion of New York

Application February 4, 1943, Serial No. 109,449

Term of patent 14 years

To all whom it may concern:

Be it known that I, Christopher M. Cordley, a citizen of the United States, residing in the city, county, and State of New York, have invented a new, original, and ornamental Design for a Water Cooler, of which the following is a specification, reference being had to the accompanying drawing, forming a part thereof.

Figure 1 of the drawing is a perspective view of a water cooler, showing my new design; and

Figure 2 is a top plan view thereof, on an enlarged scale.

The characteristic features of my design reside in the top portion of a water cooler having the configuration illustrated, and in which a bubbler is mounted on each of the two laterally extending portions of the water cooler top, all as shown in full lines in the drawing.

I claim:

The ornamental design for a water cooler, as shown and described.

CHRISTOPHER M. CORDLEY.
